UNITED STATES PATENT OFFICE

HERMANN S. SCHULTZE, OF GRIESHEIM-ON-THE-MAIN, GERMANY, ASSIGNOR TO I. G. FARBENINDUSTRIE AKTIENGESELLSCHAFT, OF FRANKFORT-ON-THE-MAIN, GERMANY

METHOD OF PRESERVING DIBASIC CALCIUM HYPOCHLORITE

No Drawing. Application filed July 25, 1927, Serial No. 208,410, and in Germany August 18, 1926.

This invention relates to a method of preserving the dibasic calcium hypochlorite $2\text{Ca}(\text{OH})_2 \cdot \text{Ca}(\text{OCl})_2$ described in my former specifications Patent Nos. 934,467 and 5 1,583,421. According to the method therein described the dibasic hypochlorite is obtained in the form of flat hexagonal crystals the size of which permits an easy separation of the salt from the mother liquor by centrifuging. In this way a product is obtained containing about 40% of active chlorine and 5-10% of moisture.

It was hitherto considered necessary to free the product from moisture as completely as possible, preferably by heating. The chemists were guided in this respect by former experiences with high grade hypochlorites (see German Patent No. 418494) and bleaching powder (see British Patent No. 242,805); 20 in order to desiccate these materials as completely as possible, it has already been proposed to add calcium oxid, or to treat the material with calcium oxid after preliminary dehydration, for instance with hot air.

Now I have found that the dibasic calcium hypochlorite is stable even if containing a water content up to about 15%. By this fact the manufacture of the dibasic calcium hypochlorite is considerably simplified and accelerated in so far as it is no more necessary to subject the centrifugated salt to a special drying process and not even to a washing process. The dibasic calcium hypochlorite is rather practically stable in the state in which it is obtained after the centrifuging process. Even at elevated temperatures the durability is superior to that of common bleaching powder to a surprising extent and practically equals that of the dried dibasic salt, so that the moist product coming from the centrifuge is as tropic-proof as the perfectly dried salt. Whereas bleaching powder at 45° C. loses about 1% of active chlorine per day and is therefore nearly completely 40 decomposed in a little over a month, the percentage of active chlorine in the moist dibasic hypochlorite as delivered by the centrifuge only decreases from 40 to 36-37% under the same conditions.

50 "Moist as delivered from the centrifuge"

means, in the sense of my invention, a degree of moisture which, independent of the means employed for obtaining it, varies from about 5 to about 15%, permits desiccation to be dispensed with and, on the other hand, reduces 55 the costs of transport to a minimum.

Thus by doing away with the desiccation of the dibasic salt the manufacture is considerably simplified and accelerated without injuring the qualities and the durability of 60 the product. Further advantages of my improved method are that the product practically does not agglomerate to lumps, that it is dustless and odorless and that, in desirable contradistinction to bleaching powder, it 65 does not at all attack the wooden transport casks, so that they can be used repeatedly.

I claim:—

1. The method of handling dibasic calcium hypochlorite which comprises packing the 70 salt into casks in the state in which it is obtained by centrifugating the wet salt.

2. The method of handling dibasic calcium hypochlorite which comprises packing the salt, containing from 5 to about 15% of moisture, into casks.

In testimony whereof I have hereunto set my hand.

HERMANN S. SCHULTZE.
